CLAIM

The ornamental design for a part for electronic cigarette, as
shown and described.

DESCRIPTION

FIG. 1 is a perspective view of a part for electronic cigarette, according to a first embodiment of our new design;

FIG. 2 is a right side view thereof;

FIG. 3 is a left side view thereof;

FIG. 4 is a front view thereof;

FIG. 5 is a rear view thereof;

FIG. 6 is a top view thereof;

FIG. 7 is a bottom view thereof;

FIG. 8 is a perspective view of a part for electronic cigarette, according to a second embodiment of our new design;

FIG. 9 is a right side view thereof;

FIG. 10 is a left side view thereof;

FIG. 11 is a front view thereof;

FIG. 12 is a rear view thereof;

FIG. 13 is a top view thereof; and,

FIG. 14 is a bottom view thereof.

The broken lines in the drawings depict portions of the part for electronic cigarette that form no part of the claimed design. The portion of FIG. 14 shown in a lighter tonal value within the broken line perimeter illustrates a portion of the part for electronic cigarette that forms no part of the claimed design.
